S. W. Gibbs of Albany, N.Y.

Assignor to

North, Chase & North of Philadelphia, Pa.

Letters Patent No. 596. — Dated Sept. 6th, 1853.

The schedule referred to in these Letters Patent, and making part of the same.

To all whom it may concern:

Be it known, that I, S. W. Bibbs of Albany, in the County of Albany, and State of New York, have invented a new design for stoves; and I do hereby declare that the following is a full and exact description thereof, reference being had to the accompanying drawings and to the letters of reference marked thereon.

The principal feature of the design is a foliated boss, B, in the center of a series of convex waved rays, a, the whole forming a raised shield in the middle of a panel. A is an ornamental border formed by clusters of lances, b, alternating with single lances springing from a section of a sphere c. d, e, are ornamental scrolls for the corners of panels. f is a border of linked bosses for the lower portion of the plates. g, is a beaded border for the door and hearth plate. h, is a convex serrated border for the top plate. At i, i, i, the convex waved rays a, are used in combination with a simple unfoliated boss B'.

Fig. 1 represents a top plate.

Fig. 2 " " hearth plate.

Fig. 3 " " side plate,

Fig. 4 " " front plate and door,

Fig. 5 " " back plate,

Fig. 6 " " foot.

What I claim as my invention, and desire to secure by Letters Patent, is the raised shield B'a, the raised shield B'i, the lance border A'b, the scrolls d, e, and the borders f, g, h, forming an ornamental design for a stove.
